UNITED STATES PATENT OFFICE.

WILLIAM H. HERZOG, OF BALTIMORE, MARYLAND.

DESIGN FOR A SCARF.

SPECIFICATION forming part of Design No. 17,847, dated November 1, 1887.

Application filed September 29, 1887. Serial No. 251,156. Term of patent 14 years.

To all whom it may concern:

Be it known that I, WILLIAM H. HERZOG, a citizen of the United States, residing at Baltimore, in the State of Maryland, have invented 5 and produced a new and original Design for Scarfs, of which the following is a specification, reference being had to the accompanying drawings, forming part thereof, in which—

Figure 1 is a plan view of my newly-designed 10 scarf, and Fig. 2 is a view of the same tied.

The leading feature of the design consists in >-shaped points on a scarf having ends of different lengths but the same width, and a narrow intermediate or neck portion.

15 A represents the scarf, which has the wide ends *a b* of different lengths, and *c* the intermediate narrow or neck portion.

B represents the >-shaped points or extremities of the ends *a b*.

Having thus described my invention, what 20 I claim as new, and desire to secure by Letters Patent, is—

The design for a scarf herein shown and described, the same consisting in the wide ends *a b*, of approximately the same width, of different lengths, and having the >-shaped extremities *B* and the intermediate narrow 25 neck portion, *c*.

WM. H. HERZOG.
